Patented Apr. 18, 1922.

INVENTOR

William D. M. Howard.

UNITED STATES PATENT OFFICE.

WILLIAM DAVIS MERRY HOWARD, OF BOSTON, MASSACHUSETTS.

FUEL-MIXING DEVICE.

1,413,227.

Specification of Letters Patent. Patented Apr. 18, 1922.

Application filed May 31, 1918. Serial No. 237,558.

To all whom it may concern:

Be it known that I, WILLIAM D. M. HOWARD, a citizen of the United States, and a resident of the city of Boston, county of 5 Suffolk, and State of Massachusetts, have invented new and useful Improvements in Fuel-Mixing Devices for Use in Connection with Internal-Combustion Engines, of which the following description, in connection 10 with the accompanying drawing, is a specification, like characters on the drawing representing like parts.

This invention has for its object to provide a novel mixing device adapted to be 15 used with internal combustion engines for the purpose of securing a more perfect mixture of the explosive charge before it is delivered to the intake manifold. My improved mixing device is constructed not 20 only to improve the mixture, but also to heat the latter thereby providing an explosive charge which is in the best condition for securing most efficient results in the engine.

My improved mixing device is especially 25 useful and effective in vaporizing and gassifying heavy or light grade petroleum oils or alcohol or other fuel oil which cannot be successfully used with the ordinary carburetor.

My improved mixing device comprises a 30 casing having a heating chamber therein through which the heated products of combustion from the engine pass and a system of ducts or passages extending through the heating chamber and through which the fuel 35 charge passes on its way from the carburetor to the intake manifold of the engine, such ducts or passages being so arranged that the fuel charge will pass through the heating chamber a plurality of times and will thus 40 become thoroughly heated. These ducts or passages are also constructed so as to secure a thorough mixing of the fuel charge in its passage therethrough.

In order to give an understanding of my 45 invention, I have illustrated in the drawings a selected embodiment thereof which will now be described, after which the novel features will be pointed out in the appended claims.

50 In the drawings, Fig. 1 is a longitudinal section of my invention, the cover being removed;

Fig. 2 is a longitudinal section when the device is turned half way around from the 55 view shown in Fig. 1;

Fig. 3 is a plan view of the body portion;

Fig. 4 is a sectional view of the body taken on the line 4—4, Fig. 2;

Fig. 5 is a sectional view of the body taken on the line 5—5, Fig. 1;

Fig. 6 is a plan view of the under side of the body showing the flange formed integral therewith;

Fig. 7 is a sectional view of the cover;

Fig. 8 is a section of the cover turned half 65 around from the view shown in Fig. 7.

Fig. 9 is a top view of the cover;

Fig. 10 is a bottom view of the cover shown in section in Figs. 7 and 8.

My device comprises a cylindrical casing 70 1 having an internal heating chamber 13 and having two laterally-extending projections 7 and 8 which provide inlet and outlet passages 14 and 15 leading to the heating chamber 13. These hollow projections 7 and 8 75 are adapted to be connected to the exhaust manifold in such a way that the exhaust gases from the engine will enter the inlet 14, pass through the chamber 13 and be discharged through the outlet opening 15. 80

The casing 1 is provided at its lower end with a flange 2 which is adapted to be connected to the usual carburetor, said flange having tapped holes 30 to receive the screws or bolts by which the device is connected to the carburetor. The casing 1 is formed with a body portion and with a cover portion 4 which is screw-threaded to the body, said body having the upwardly-extending flange or rim 6 provided with the interior screw-threads 5 to which the cover is screwed. The cover is provided with tapped apertures 30 to receive bolts or screws by which the device is attached to the intake manifold of the engine. The body is provided with a central 90 passage 12 extending through the chamber 13, said passage being bounded by the tubular wall 11 and opening at its lower end through the bottom of the casing, said casing 12 having communication, therefore, directly with the carburetor.

The cover 4 is provided with an outlet opening 23 which communicates with the intake manifold and the device is provided with a plurality of passages or ducts which 105 form a communication between the casing 12 and the outlet 23 and through which the fuel charge is passing, these passages making a circuitous route for the fuel charge through the heating chamber 13. 110

The cover 4 is formed with a chamber 26 which communicates with the upper end of

the passage 12, and the casing is also provided with a plurality of passages indicated at 17, 18, 19 and 20 which extend through the chamber 13 and are situated exterior to the central passage 12. These passages 17, 18, 19, 20 are enclosed by curved walls 21 and they all communicate at their lower end with an annular space 16 in the bottom of the casing which surrounds the tubular wall 11. Two of the passages or ducts, to wit: the passages 17 and 19, communicate at their upper end with the space 26, and the other two passages, to wit: the passages 18 and 20, communicate at their upper end with passages or ducts 25 in the cover 4 which lead to a chamber 24 in said cover, said chamber communicating with the outlet 23. When the cover and body are assembled, there will, therefore, exist a continuous but circuitous passage through the device for the fuel charge, this passage consisting of the passage 12, chamber 26, ducts or passages 17, 19, chamber 16, ducts or passages 18, 20, passages 25, chamber 24, and outlet 23. The fuel charge, therefore, passes through the heating chamber three times. Once up through the passage 12, a second time down through the passages 17 and 19, and a third time up through the passages 18 and 20, and during its triple passage through the heating chamber it becomes thoroughly heated.

The walls of the passage 12 are preferably rifled, as shown in Fig. 1, so as to assist in giving a swirling action to the fuel charge.

I have also shown a jet nozzle 32 which communicates with the heating chamber 13 and opens into the passage 12. Some of the products of combustion will be delivered through this jet nozzle into the passage 12 and will thereby assist in securing a more perfect mixture by increasing the agitation of said mixture.

When the device is in use, the suction created in the intake manifold by the operation of the engine will draw the fuel charge from the carburetor through the circuitous passage above described, and in passing through this circuitous passage the fuel charge becomes thoroughly mixed. As soon as the engine starts the hot products of combustion will pass through the heating chamber 13, and thus heat the charge. As a result of this operation an explosive mixture is produced which will give maximum efficiency and will burn without the formation of carbon residue. Moreover, the construction of the device is such that the fuel mixture is brought into intimate contact with a maximum area of heating and mixing surfaces in a minimum space.

I may, if desired, employ a cylindrical platinum screen mounted in the chamber 16,

the presence of which serves to more effectively mix the fuel and to condition the fuel mixture which passes therethrough so as to provide a gas which will ignite and explode more easily under conditions of temperature and compression met with in the ordinary gas engine.

I claim:

1. In a device of the class described, a casing comprising a body section having a heating chamber provided with an inlet and an outlet, whereby hot products of combustion may pass through said chamber, said body section also having a central passage which extends therethrough and an inlet for a gaseous mixture leading to said central passage, 80 said body section further having two sets of connected intermediate passages extending through the heating chamber, and a cover section having an outlet for said gaseous mixture, a space connecting certain of said intermediate passages to said outlet, and a chamber which communicates both with the other intermediate passages and with the central passage.

2. In a device of the class described, a casing comprising a body section having a heating chamber therein, provided with an inlet and an outlet whereby hot products of combustion may pass through said chamber, said body section also having a central passage extending therethrough and which terminates at one end of said section in an inlet for gaseous mixture and two sets of intermediate passages surrounding the central passage and extending through the heating chamber, said body section further having a chamber surrounding the central passage and with which said intermediate passages communicate, and a cover section having an outlet for the gaseous mixture, a space or chamber connecting said outlet with certain of said intermediate passages and a separate space connecting the central passage with the other intermediate passages.

3. In a device of the class described, a casing comprising a body section having a heating chamber through which hot products of combustion may pass, a plurality of passages for a gaseous mixture extending through the heating chamber, one of said 115 passages leading to an inlet, and a cover section secured to the body section and having an outlet, a passage connecting said outlet with certain of said passages and a space forming a communication between the other 120 passages.

In testimony whereof I have affixed my signature, in presence of two witnesses:

WILLIAM DAVIS MERRY HOWARD.
